UNITED STATES PATENT OFFICE.

FREDERICK W. HEMPELMANN, OF CINCINNATI, OHIO.

REWINDING DEVICE FOR SELECTOR-SHEETS.

1,097,020.

Specification of Letters Patent.

Patented May 19, 1914.

Original application filed May 22, 1912, Serial No. 698,875. Divided and this application filed February 12, 1913. Serial No. 747,892.

To all whom it may concern:

Be it known that I, FREDERICK W. HEMPELMANN, a citizen of the United States, residing at Cincinnati, in the county of Hamilton and State of Ohio, have invented certain new and useful Improvements in Rewinding Devices for Selector-Sheets, of which the following is a specification.

My invention relates to automatic musical instruments, and has for its object the regular and accurate operation of the selector sheet of the instrument, while at the same time permitting ready removal and insertion of the selector sheet.

15 The invention consists in the parts and in the details of construction and arrangement of parts, as will hereinafter be more fully described and claimed.

In the drawings: Figure 1 is a front elevation of a device embodying my invention. Fig. 2 is a vertical cross section, looking to the right, on a line corresponding to the line $x-x$ of Fig. 1. Fig. 3 is a partial longitudinal vertical section, on a 25 line corresponding to the line $y-y$ of Fig. 2, this view being somewhat enlarged.

In the device here exemplifying my invention, the perforated sheet 1 is wound from the upper spool 2 onto the lower spool 3 during the rendition of the music, passing over the tracker board 4, which has a series of orifices 4', through which air is admitted when the corresponding perforations 1' of the sheet pass over them. Through these 35 orifices the air acts, by means of suitable mechanism, upon the instrument, in any of a number of ways familiar to those skilled in the art of constructing self-playing musical instruments. When the playing of the 40 piece of music is completed, the sheet is rewound onto the upper spool, for repetition, or for removal of the spool with the sheet, ready for the insertion of another spool with a different sheet or selector, to play a different piece of music.

A suitable driving mechanism 5, and preferably, a pneumatically operated automatic reversing mechanism 6, are provided, both of which are fully described in my Patent 50 No. 1,055,276, dated March 4, 1913, of the application for which this application is a division; and in another division of the above named application, Serial No. 747,893, filed Feb. 12, 1913. The connection of these 55 mechanisms with the spools will be described later.

As shown, the spools 2 and 3 are supported in a frame 4^a which also supports the tracker-board 4. The lower spool 3 is simply mounted at one end on a yieldable bearing 3', allowing it to be inserted in the frame, and makes engagement at the other or driving end with a main arbor 7, journaled in a bearing 7' in a plate 7" that is fastened to the outside of the frame 4^a, said bearing projecting through the frame at this point.

The upper spool 2 is mounted at one end on a yieldable bearing 2', and at its driving end on a re-winding arbor 8, likewise journaled in a bearing 8' in the plate 7", projecting inside the frame 7. The mounting of the upper spool is illustrated in detail in Fig. 3, and the mounting of the lower spool may be understood from the description of this upper mounting, especially with reference to the yieldable bearing.

This yieldable bearing comprises a plunger 2^a which receives the spindle 2" of the spool 2 and compresses a spring 2^{a'} in a 80 casing 2^b around its stem 2^{a''} that extends through the rear end of the casing and has a knob 2^{a'''} for taking hold to manipulate the bearing during insertion of the spool as may well be understood from inspection of 85 the drawing. The lower yieldable bearing is identical with the upper one, having, as may be seen in Fig. 1, a plunger 3^a receiving the spindle 3" of the spool 3, and having a casing 3^b from which the stem 3^{a''} protrudes with the knob 3^{a'''} thereon.

The upper driving-end mounting is different from the lower driving-end mounting chiefly in that the upper one is adjustable so that the upper spool may be accurately aligned with the lower spool. Thus, the re-winding arbor 8 is hollow throughout and has its bore somewhat enlarged at one end, to receive the forward spindle 2" of the spool 2. A diametral slot 8" crosses 100 this enlarged spindle-receiving part of the bore, opening from this end of the shaft, and receives diametrically extended lugs 2''' on the spindle. The slot 8" is long enough to allow enough movement of the 105 lugs 2''' therein to provide the desired adjustment of the upper spool with respect to the lower one. The re-winding arbor 8 has another enlargement to its bore at its other end, and this is threaded and receives 110 an enlarged threaded part of a pin 8^a that extends its unenlarged part through the un-

enlarged part of the bore in the arbor, and engages its end with the end of the spindle 2^{'''} of the spool 2. The outer end of this pin 8^a has a knob 8^a, and by turning the pin 5 to screw it in or out, the spool 2 will move longitudinally, against or with the pressure of the spring 2^a in the yieldable bearing. The lower main arbor 7 receives the spindle 3^{'''} of the lower spool 3 in the manner above 10 described, but there is no pin for adjusting the spool 3.

It will be seen that with the above-described mountings the spools will be rotated with their respective arbors, but may be re- 15 moved and like spools with different perforated sheets or selectors inserted, which is a requirement peculiar to self-playing musical instruments generally in use.

By having the longitudinal adjustment of 20 the upper spool, the spools may be readily alined, and avoid buckling and undue strain on any one part of the perforated sheet, while keeping it close to the tracker board at all times.

25 For driving the sheet in its downward travel, to play the music, the main arbor 7 has a spur gear 9 fixed to it outside the bearing 7', and for re-winding the sheet, the re-winding arbor 8 has a spur gear 10 fixed to it outside the bearing 8'. Collars 7^{'''} and 8^{'''}, inside the bearings, prevent end play of the arbors 7 and 8, respectively.

The gear 10 has a sheave 10^a turning with it, and a shoe 10^b bears on this sheave during 35 the downward travel of the sheet, to prevent racing of the upper spool. A flat spring 7^a bears on the gear 9, below, to similarly control the lower spool during re-winding. This flat spring is allowed to 40 bear constantly, but the shoe 10^b, above, is controlled so as to be released from engagement with the sheave 10^a during the re-winding, by engagement of a pin 10^c, mounted on the reversing mechanism. This 45 reversing mechanism comprises a slidable bracket 11, carrying pinions 12 and 13, which may mesh with the spur gear 9 and pinion 10, below and above, respectively, alternatively. The operation of the driving 50 mechanism 5 is such that the intermeshing of the pinion 12 and gear 9 will wind the sheet for playing, and the intermeshing of the pinion 13 and pinion 10 will rewind the sheet. The bracket 11 has an arm 11^a, enter- 55 ing a stirrup 14 on a bar 15, which is raised or lowered by a sliding cam 16, connected to the pneumatic reversing mechanism 6 by the strut 17. This mechanism is connected by tubes 6^a to suitable apertures in 60 the tracker board 4, and the sheet has corresponding perforations, such as the perforation 6', which, admitting air, causes the pneumatic mechanism 6 to act.

65 Springs 11' are interposed, inside the stirrup 14, between its upper and lower insides

and the adjacent sides of the arm 11^a, to cushion the impact of the teeth of the respective gears and pinions, as they intermesh.

The spiral cam 18, driven by a worm 19 and worm gear 20 from the arbor 7, controls, through the bell-crank 21, the speed of winding of the sheet on the lower spool 3, by sliding the wheel 22 across the face of the disk 23, of the driving mechanism 5. 75 This wheel 22 connects to the lower pinion 12 by means of the articulated shaft 24, and the other pinion 13 connects to other parts of the driving mechanism through the articulated shaft 25. 80

By means of the above described construction, the reversible driving mechanism is mounted for positive action, and for accurate control thereof, while the spools are readily removable and adjustable, but under accurate control of the reversible driving mechanism at all times while in place for operation. The entire driving mechanism is rendered independent of the frame 90 4^a, by having the immediate parts of the mechanism all mounted on the single plate 7'', which may be of metal, while the frame 4^a may be of wood, as is desirable in constructing this part of an automatic musical instrument. 95

Having fully described my invention, what I desire to secure by Letters Patent is:

1. In a re-winding device, in combination with a perforated selector sheet and a tracker board over which the sheet travels, a frame 100 supporting the tracker board, a main spool, a rewinding spool, a main arbor for the main spool, a re-winding arbor for the re-winding spool, means for the engagement and disengagement of the spools with their respective arbors, one of said arbors having a central bore, and a pin screwed into said arbor through said bore, engaging to adjust said re-winding spool axially, to aline said selector sheet. 105

2. In a rewinding device, in combination with a perforated selector sheet and a tracker board over which the sheet travels, a frame supporting the tracker board, yieldable bearings in the frame, spools carrying 115 the sheet and turning in the yieldable bearings, arbors for the spools journaled in the frame, means for engagement and disengagement of said spools with their respective arbors as permitted by their yieldable 120 bearings, and whereby said spools are rotated by said arbors, one of said arbors having a central bore, and a pin screwed into said arbor through said bore, engaging to adjust said re-winding spool axially, to aline 125 said selector sheet.

3. In a re-winding device, in combination with a perforated selector sheet and a tracker board over which the sheet travels, a frame supporting the tracker board, spools 130

carrying the sheet, yieldable bearings for the spools in the frame, a plate on the frame, arbors, and bearings for the arbors in the plate, means for engagement and disengagement of said spools with their respective arbors as permitted by their yieldable bearings, and whereby said spools are rotated by said arbors, toothed wheels turning with the arbors, a slideable bracket on said plate, and toothed wheels rotatable on the bracket, and intermeshed alternatively with respective ones of the toothed wheels on the arbors, as the bracket slides on the plate, for the purposes set forth.

15 4. In a re-winding device, in combination with a perforated selector sheet and a tracker board over which the sheet travels, a frame supporting the tracker board, spools carrying the sheet, yieldable bearings for 20 the spools in the frame, a plate on the frame, arbors, and bearings for the arbors in the

plate, means for engagement and disengagement of said spools with their respective arbors as permitted by their yieldable bearings, and whereby said spools are rotated by 25 said arbors, toothed wheels turning with the arbors, a slideable bracket on said plate, and toothed wheels rotatable on the bracket, and intermeshed alternatively with respective ones of the toothed wheels on the arbors, as 30 the bracket slides on the plate, a sheave turning with one of the arbors, a brake engaging the sheave, and means on said bracket to disengage the brake from the sheave when the respective toothed wheel 35 on the bracket is meshed with the toothed wheel on the arbor having the sheave, for the purposes set forth.
